(57) **CLAIM**

The ornamental design for a plate for holding plurality of reaction vessels, as shown and described.

DESCRIPTION

FIG. 1 is a top plan view of a plate for holding plurality of reaction vessels showing our new design;

FIG. 2 is a bottom plan view thereof;

FIG. 3 is a front elevational view thereof, the rear elevational view thereof being a mirror image of the front elevational view;

FIG. 4 is a right side elevational view thereof; and,

FIG. 5 is a left side elevational view thereof.

The broken lines are included for the purpose of illustrating portions of the plate for holding plurality of reaction vessels that forms no part of the claimed design.
